UNITED STATES PATENT OFFICE.

HORATIO FAIRBANKS, OF BOSTON, MASSACHUSETTS.

IMPROVEMENT IN LAMP-BURNERS.

Specification forming part of Letters Patent No. 42,281, dated April 12, 1864.

To all whom it may concern:

Be it known that I, HORATIO FAIRBANKS, a resident of Boston, in the county of Suffolk and State of Massachusetts, have invented a new and useful Improvement in Lamps; and I do hereby declare the same to be fully described in the following specification, and represented in the accompanying drawings, of which—

Figure 1 denotes a side elevation, and Fig. 2 a vertical section, of a lamp-cap, screw, and wick-tube provided with my invention.

The purpose of my invention or improvement is to supply the flame of a wick with oxygen and prevent such flame from smoking, particularly when a light hydrocarbon fluid—such as petroleum-naphtha or coal-oil naphtha, kerosene, or such like fluid—may be used in or with the wick.

In Fig. 2 of the drawings, A denotes a wick-tube projecting upward from the lower part of a conical tube, B, which circumscribes the tube A and extends downward from the screw-cap C of a lamp, the said cap C, when in use, being screwed into the cap of the neck of the oil-reservoir of a lamp and so that the part B may extend into such reservoir. The tube B forms a chamber, *a*, which encompasses the wick-tube A, and is closed at bottom and open at top. Another tube, D, extends around the wick-tube A and within the chamber *a*, and is so adapted to the tube A as to be capable of being raised or depressed thereon. The lower part or end of the tube D fits closely on the tube A, the upper end of the bore of the tube D having a diameter larger than that of the tube A, in order to form around the said tube A an air-chamber or space, *b*. Openings *c c*, are made laterally through the tube D, or that part of it which is within the chamber *a*, in order that air for supply of the flame of the wick may pass into the tube D or down into the chamber *a*, and from thence flow into the openings *c c* and enter and pass up through the chamber *b*. By raising the tube D on the

tube A until the top of the former may come in or very nearly in contact with the flame of the wick (when the tube A may be supplied with a wick and the latter may contain a combustible fluid inflamed at its top) the flame will not only be supplied with air, but will be prevented from emitting smoke. While the tube B and its chamber *a* operate to prevent the heat of the flame from being conducted by the wick-tube into the fluid of the lamp-reservoir so as to heat the same, and while the tube D operates to supply the flame with oxygen and prevent it from smoking, the air for the supply of combustion, by being caused to pass down within the chamber *a*, will abstract heat from the tube A and from the tubes B and D, and thus not only prevent the fluid within the lamp-reservoir from becoming heated, but prevent the tube B from being burned or injured by the flame.

I do not claim the combination of the tube B and its chamber *a* with the screw-cap C and its wick-tube A, nor do I claim a stationary cone or deflector or air-conduit combined with a wick-tube and for the purpose of supplying the wick with air.

What I claim, and desire to secure by Letters Patent, is as follows:

1. The combination of the adjustable air-supplying tube or conduit D with the wick-tube A, the said conduit being movable vertically on the wick-tube and provided with air-entrance openings, substantially as described.

2. The combination and arrangement of the air-supply tube D and its air-inlets, with the wick-tube A and the circumscribing chamber *a*, formed by the conical tube B, extending down from the screw-cap C, substantially as specified.

HORATIO FAIRBANKS.
